UNITED STATES PATENT OFFICE.

WILLIAM A. DUNLAP, OF PITTSBURGH, PENNSYLVANIA.

BASIN.

1,075,341.

Specification of Letters Patent. Patented Oct. 14, 1913.

Application filed May 27, 1912. Serial No. 699,899.

To all whom it may concern:

Be it known that I, WILLIAM A. DUNLAP, residing at Pittsburgh, in the county of Allegheny and State of Pennsylvania, a citizen of the United States, have invented or discovered certain new and useful Improvements in Basins, of which improvements the following is a specification.

The invention described herein relates to certain improvements in basins, sinks, etc., of the class or kind described and claimed in an application filed by me on May 6th, 1908, Ser. No. 431,387.

In the accompanying drawings forming a part of this specification Figure 1 is a sectional elevation of a wash-bowl embodying my improvements; Figs. 2, 3 and 4 are views illustrative of the steps involved in the formation of the connection from the overflow to the discharge outlet.

In the practice of my invention the bowl 1, roll 2, apron 3 and back-piece 4 are formed preferably by stamping from a sheet of sheet steel. In the stamping operation a portion of the wall of the bowl is pressed outwardly to form a U-shaped groove 5 as shown in Fig. 2. By means of suitable tools known in the art the metal at the junction of this U-shaped portion and the wall of the bowl is gradually forced inward as shown in Figs. 3 and 4 to form a closed tube 7 shown in Fig. 4. In closing in the edges of the U-shaped portion suitably shaped plugs are inserted where the overflow and the discharge outlets are to be formed so that when closing the edges of the groove openings

will be left as indicated at 8 and 9 for these outlets. The opening 10 for connection with the waste pipe is preferably formed prior to the closing in of the edges of the U-shaped portion to form a tube. The meeting edges ⁴⁰ *a* of the tube are preferably welded or brazed together as indicated in Fig. 4. After the bowl has been completed a continuous unbroken coating of protecting material, preferably enamel, is applied to all the surfaces both interior and exterior, by dipping the bowl in a bath of the material of which the coating is to be formed. In addition to covering the surfaces both ⁴⁵ *interior* and exterior of the bowl and the overflow pipe this coating will hermetically seal all the joints. ⁵⁰

I claim as my invention:

1. A basin, sink, etc., formed of sheet ⁵⁵ metal and provided with overflow and discharge openings, and having its wall bent to form a tubular conduit connecting said openings.

2. A basin, sink, etc., formed of sheet ⁶⁰ metal and provided with overflow and discharge openings, and having its wall bent to form a tubular conduit connecting said openings, the basin and conduit having all interior and exterior surfaces covered by a ⁶⁵ continuous coating of enamel.

In testimony whereof I have hereunto set my hand.

WILLIAM A. DUNLAP.
